UNITED STATES PATENT OFFICE.

MILTON H. SHOENBERG, OF SAN FRANCISCO, CALIFORNIA, ASSIGNOR OF ONE-HALF TO BERNARD LOWENSTEIN, OF SAN FRANCISCO, CALIFORNIA.

ELECTRICAL FLUID-HEATER.

No. 859,851.

Specification of Letters Patent.

Patented May 7, 1907.

Application filed September 13, 1906. Serial No. 334,410.

To all whom it may concern:

Be it known that I, MILTON H. SHOENBERG, a citizen of the United States, residing at the city and county of San Francisco and State of California, have invented new and useful Improvements in Electrical Fluid-Heaters, of which the following is a specification.

My invention relates to an apparatus which is designed for heating fluids.

It consists in the combination of a heating chamber in connection with a reservoir, a circulating tube located within the chamber, and an insulated high resistance conducting wire through which heat is transmitted to the contents of the chamber; and in details of construction which will be more fully explained by reference to the accompanying drawings in which—

The figure is a central vertical section of my apparatus.

It is the object of my invention to provide an apparatus whereby considerable quantities of fluid may be raised to and maintained at an elevated temperature.

In the drawings I have shown a reservoir A which may be of any desired size, shape and proportions. Connected with this reservoir is a chamber 2 which is closed at the bottom and which has an open upper end which may be inserted into the bottom of the reservoir A.

I have here shown the upper end of the chamber 2 as screw-threaded, and by means of washers 3 which screw upon this threaded portion within and outside of the bottom of the reservoir, it will be seen that the chamber may be detachably secured to the reservoir and a tight joint formed therewith.

Within the chamber 2 is secured a tube 4 preferably located centrally within the chamber and having holes 5 around the lower part through which the fluid within the reservoir and chamber may be circulated as will be hereafter described.

Exterior to the walls of the chamber 2 is an insulating material 6, such as sheet mica, or other substance, which will not materially interfere with the passage of heat through the walls of the chamber while at the same time presenting an effective insulation for the wires 7 which are coiled about the exterior of the insulation 6. These wires are naked wires and are coiled so that the con-

tiguous turns of the wire are out of contact with each other and short-circuiting will thus be prevented. Around the upper portion of this insulation I have shown a metallic ring or collar 9 and with this, one portion of the line wires 10 is connected. One end of the wire 7 is connected with this ring as shown at 11, and the other end is connected with a similar ring or equivalent conductor 12 at the lower end of the chamber. From this lower ring connection is made with a switch 13, and thence with the line wire 14 whereby the circuit may be completed. The whole of this portion of the apparatus is inclosed in a housing or casing 16 which may be secured to the chamber by means of a screw 15 passing through the bottom of the housing and into the bottom of the casing 2, or by any equivalent or suitable means.

The operation of the apparatus will then be as follows: The reservoir A being filled with water or other fluid which it is desired to heat, and an electrical circuit being established through the resistant coil 7, the heat from the coil will be transmitted through the thin insulating jacket, and the walls of the chamber 2, and the fluid within the chamber and contiguous to the walls thereof will be caused to rise by reason of its increase in temperature and expansion. At the same time the cooler liquid from the reservoir A will be caused to flow downwardly through the tube 4 and passing out through the openings 5 at the bottom of the tube, it will be delivered into the exterior part of the chamber to take the place of the fluid which is constantly rising into the reservoir. By this means a circulation will be established so that the contents of the reservoir will be heated and a constant temperature may be maintained within the reservoir which is thus capable of supplying a considerable body of heated fluid; the amount and temperature depending upon the capacity of the heating coil.

Having thus described my invention, what I claim and desire to secure by Letters Patent is—

1. A fluid heating apparatus consisting of a reservoir, a metallic chamber connected therewith having an insulating casing, a resistance coil inclosing said casing with electrical connections whereby the temperature of the chamber may be raised and a tube centrally disposed within the chamber, said tube

having its upper end in open communication with the reservoir and openings near the bottom whereby a circulation of fluid may be effected.

5 2. An electrical fluid heater consisting of a metallic open top chamber, having an insulating inclosing material, naked wires coiled upon said insulation out of contact with each other, means for supplying an electrical current whereby the wires and the chamber are heated, a tube fixed centrally within the chamber having an open upper end and openings through the bottom communicating with the interior of the chamber, and a reservoir with the lower part of which the chamber and tube are in open communication.

3. In an electrical water heater, an insulated chamber, an electrical resistance coil inclosing said chamber, means for transmitting an electrical current through the coil, a tube located centrally within the chamber having an open upper end and holes around the bottom, a reservoir having an opening in the bottom into which the upper end of the 25 chamber extends, and washers whereby the

chamber is removably clamped in said opening and a tight joint formed.

4. In an electrical fluid heater, an insulated open topped water chamber having a central open topped tube with openings around the bottom connecting with the lower interior part of the chamber, a reservoir having an opening in the bottom to receive the upper end of the chamber, clamping washers by which the chamber is removably secured from the reservoir, an insulating jacket surrounding the chamber, a resistance coil inclosing the insulation, metallic rings with which the upper and lower ends of the coil connect, electrical conducting wires connecting with the rings and a switch whereby an electrical current may be transmitted through the coil or interrupted.

In testimony whereof I have hereunto set my hand in presence of two subscribing witnesses.

MILTON H. SHOENBERG.
